COMBINED EXTENSION BED AND SETTEE

Melvin Smilow, White Plains, and Morton Thielle,
Forest Hills, N. Y.

Application May 22, 1953, Serial No. 25,171

Term of patent 14 years

(Cl. D5—4)

Fig. 1 is a perspective view of the frame element of a combined extension bed and settee embodying our new design, the mattresses being omitted for convenience of illustration, and showing the frame in open position.

Fig. 2 is a side elevational view of the combined bed and settee with parts of the rear legs broken away for convenience of illustration.

Fig. 3 is a side elevational view thereof in position for use as a settee.

Fig. 4 is a front elevational view of the combination on a reduced scale.

The dominant features of the design reside in the portions shown in full lines, the conventional spring support being fragmentarily shown in broken lines for illustrative purposes only.

We claim:

The ornamental design for a combined extension bed and settee, as shown and described.
